UNITED STATES PATENT OFFICE

147,251

DESIGN FOR A HOBBYHORSE

Francis H. McClernon, Springfield, Mo.

Application January 29, 1946, Serial No. 126,068

Term of patent 14 years

(Cl. D34—15)

To all whom it may concern:

Be it known that I, Francis H. McClernon, a citizen of the United States, residing at Springfield, county of Greene, State of Missouri, have invented a new, original, and ornamental Design for Hobby Horses, of which the following is a specification, reference being had to the accompanying drawing, forming a part thereof.

The figure is a perspective view of a hobby horse showing my new design.

The characterizing feature of my design resides in the combination on the rocking horse of a seat bar having its ends inclined downwardly in planes parallel with upturned ends of the rockers, and a second bar between the rockers and the seat bar and parallel to the seat bar and having its ends connected to downwardly turned ends of the seat bar, the ends of the sec-

ond bar projecting below cross bars connecting the rockers, all as shown.

I claim:

The ornamental design for a hobby horse, as shown and described.

FRANCIS H. McCLERNON.
